(57) **CLAIM**

The ornamental design for an article holder with end clip, as shown and described.

DESCRIPTION

FIG. 1 is a perspective view of an article holder with end clip, showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a perspective view similar to FIG. 1 showing a cigarette lighter in dashed lines, the dashed lines being used for illustrative purposes only and forming no part of the claimed design.

1 Claim, 2 Drawing Sheets
